UNITED STATES PATENT OFFICE.

HERBERT J. LONG, OF NEW BRUNSWICK, NEW JERSEY.

SAFETY GAS APPLIANCE.

1,076,774.

Specification of Letters Patent.

Patented Oct. 28, 1913.

Application filed May 23, 1911. Serial No. 628,976.

To all whom it may concern:

Be it known that I, HERBERT J. LONG, a citizen of the United States of America, and residing at New Brunswick, in the county of Middlesex and State of New Jersey, have invented certain new and useful Improvements in Safety Gas Appliances, of which the following is a specification, such as will enable those skilled in the art to 10 which it appertains to make and use the same.

This invention relates to gas burning devices wherein a pilot light is employed in conjunction with the main gas supply, and in the present form of embodiment thereof is particularly adapted for use in connection with water heaters. In the forms of devices of this class now in use it has been found that the pilot light is sometimes extinguished and when the main gas supply is turned on, either manually or by automatic means, no ignition thereof occurs within the heater and, when an effort is made to ignite either the pilot or the main 20 burners, serious explosions result due to the volume of escaped gas within the casing of the heater and to the continued escape thereof from the burners, and it is to avoid any 25 possibility of such explosion that my invention was conceived.

The object of my invention is to provide a barrier for the pilot light, such as a door or equivalent, which is in operative connection with a valve in the main gas supply pipe 35 in such manner that when the barrier is removed to ignite the pilot, in the event of its having been extinguished, the main gas supply to the burners is shut off, the gas which had been permitted to escape from the burners passing upwardly and outwardly 40 through the flue aided by the draft occasioned by the opening of the door, when a door is employed as the barrier, and by the time a match is lighted and inserted into the heater no gas remains therein, or very little, and the flow of gas to the burners having 45 been stopped, no explosion occurs and the pilot may be lighted with perfect safety and, when the door is again closed, the safety or 50 emergency valve referred to again permits the passage of gas to the main burners where it is ignited by the pilot.

My invention is fully described in the following specification, of which the accompanying drawings form a part, in which the separate parts are designated by the same

reference characters in each of the views, and in which;—

Figure 1 is a fragmentary elevation of a water heater provided with my invention; 60 Fig. 2 is a sectional plan view thereof on the line 2—2 of Fig. 1; and Fig. 3 is a section through a valve which I employ, on the line 3—3 of Fig. 1.

In the drawings forming a part of this 65 application I have shown a preferred form of embodiment of my invention adapted for use in water heaters, said heater comprising a casing *a* having burners *a*² therein which are in connection with the main gas supply 70 pipe *a*³, said pipe being usually provided with a valve *a*⁴ to control the same, said valve being either manual or automatic, or both of such valves may be employed; and a pilot light tube *a*⁵ extends into the casing *a* 75 from a point in the pipe *a*³ beyond the valve *a*⁴ whereby a constant flow of gas is permitted therethrough, and I may employ a valve *a*⁶ in the pilot light tube if desired, all of the parts just described being of old 80 and well-known construction.

At *b* I have shown a valve interposed between the valve *a*⁴ and the burners *a*², the stem *b*² of which extends upwardly a pre-determined distance and has an arm *b*³ secured thereto to operate the same, said arm being provided with a slot *b*⁴ therein through which passes a screw or bolt *b*⁵ which is held in a door *c* hinged at *c*² and serving as a cover for an opening *c*³ in the 90 casing *a* adjacent the pilot burner *a*⁷, and it will be understood that the valve *b* is open when the door *c* is closed but, when the said door is opened, the valve *b* is closed 95 as indicated in dotted lines in Fig. 3 the slot *b*⁴ permitting the bolt *b*⁵ to slide therein in the movement of the door.

At *c*⁴, Fig. 1, I have shown a plurality of minute openings which are merely for the purpose of being able to see if the pilot light is burning, but any suitable equivalent may be employed for this purpose, the said holes not being of sufficient size to permit the entry of a match or other flaming article, and it is thus necessary to open the door *c* before access can be had to the pilot to light the same in the event of its not being lighted or of its having been extinguished in any manner.

It will be understood that the casing *a* 110 contains the usual water supply pipes, arranged in coils or other desired form to give

a large heating surface, these pipes not being shown, however, as they form no part of this invention and, from the foregoing, it will be seen that a constant flow of gas is 5 permitted to the burners when the door *c* is closed and the valve *a* open, but when the door *c* is opened the supply of gas to the burners is stopped and the pilot may be 10 lighted without fear of explosion and, while I have shown my invention adapted for use in connection with water heaters, it will be evident that it is adapted for any gas burning device wherein a constantly burning pilot light is employed and wherein explosions are possible due to escaped or escaping 15 gas, and it will also be evident that many changes in and modifications of the details of construction shown and described may be made to adapt my invention either to water heaters or other uses and still be within the 20 spirit of my invention and without sacrificing the advantages thereof.

Having fully described my invention, what I claim as new and desire to secure by Letters Patent, is:—

1. In a gas burning device, a casing provided with a door, main burners therein, a gas supply pipe for said burners, a valve in said pipe, a pilot fixed in said casing and in 30 communication with said pipe between said valve and the source of supply whereby a constant gas supply results to said pilot, and means connected with said door and valve for closing the valve upon opening the door and thus preventing the supply of gas to 35 said main burners when the door is opened.

2. In a water heater, the combination of a combustion chamber, a door therefor, a burner within the combustion chamber, a 40 fuel supply pipe leading to the burner, a valve for said supply pipe, a pilot normally in coöperative relation with the burner and in constant communication with a source of gas supply, and means actuated by the door for closing the valve on the opening of the 45 door to cut off the gas supply to the burner.

3. In a heater, the combination of a combustion chamber, a door therefor, a main burner and a pilot burner within said chamber, means for supplying fuel to said burners, a valve controlling the supply of fuel to said main burner independently of the supply of fuel to said pilot burner and means actuated by the movement of the door for 55 closing the valve upon opening the door and cutting off the supply of gas to the main burner without affecting the supply of gas to the pilot burner.

4. In a heater, a combustion chamber, a 60 door therefor, a main burner and a pilot burner in said chamber, means for supplying

fuel to said burners, a main valve for controlling the supply of fuel to said main burner, a valve for controlling the supply of fuel to said pilot burner independently 65 of the supply of fuel to said main burner and means of connection between said door and said main valve for operating said main valve when said door is open without affecting the valve controlling the supply of fuel 70 to said pilot burner.

5. In a heater, a combustion chamber, a main burner in said chamber, a fuel supply pipe leading thereto, a main valve in the supply pipe to the main burner, a door for 75 said chamber, hinges for said door independent of said valve, means of connection between said door and said valve for closing said valve upon opening said door and opening said valve upon closing said door and means for igniting the fuel from said main burner within said chamber when the door is closed.

6. In a heater, a combustion chamber, a main burner in said chamber, a supply pipe 85 leading thereto, a main valve in the supply pipe to the main burner, a door for said chamber, hinges for said door substantially in line with but independent of said valve, an arm for transmitting motion from said door to said valve to close said valve when said door is opened and adjustable means for connecting one end of said arm to one of said elements.

7. In a heater, a combustion chamber, a 95 main burner in said chamber, a supply pipe leading thereto, a main valve in the supply pipe to the main burner, a door for said chamber, hinges for said door substantially in line with but independent of said valve, 100 an arm for transmitting motion from said door to said valve to close said valve when said door is opened and adjustable means for connecting said arm to said door.

8. In a heater, a combustion chamber, a 105 main burner in said chamber, a fuel supply pipe leading thereto, a rotary valve in said supply pipe, a door for said chamber, hinges for said door substantially in line with said valve, an arm secured to said valve and having a sliding connection with said door for closing said valve when said door is opened and opening said valve when said door is closed.

In testimony that I claim the foregoing as 115 my invention I have signed my name in presence of the subscribing witnesses this 22nd day of May, 1911.

HERBERT J. LONG.
